UNITED STATES PATENT OFFICE.

PHILIPP A. DESLAURIERS, OF ST. PAUL, MINNESOTA.

DESIGN FOR A SIDING-PLATE.

SPECIFICATION forming part of Design No. 22,609, dated July 11, 1893.

Application filed October 4, 1892. Serial No. 447,824. Term of patent 14 years.

To all whom it may concern:

Be it known that I, PHILIPP A. DESLAURIERS, a citizen of the United States, residing at St. Paul, Ramsey county, Minnesota, have invented and produced a certain new and original Design for a Sheet-Metal Siding-Plate for Buildings, of which the following is a specification, reference being had to the accompanying drawings, illustrating the same, in which—
5 Figure 1 is a plan view, and Fig. 2 is a side elevation of the plate.
The siding plate is of rectangular form, and the leading features of the design, with which it is ornamented are, an irregular raised surface covered by rounded, projections 2, and resembling a pebbled surface. This surface is subdivided into different sized oblongs by means of the ridges 3, having sloping sides and a flat top, as shown best in Fig. 2. The

edge of the plate surrounding the ornamented surface, has a similar ridge or bead 4. Mitered with and projecting outward from this are the ends 5, of ridges of similar form.

The general appearance and effect of the design are, of a series of pebble surfaced oblong blocks laid in a wall to break joints in representation of irregular or broken ashlar with a ridge or raised line of mortar between.

What I claim is—

The design for a siding plate as herein shown and described.

In testimony whereof I have hereunto set my hand this 23th day of September, 1892.

PHILIPP A. DESLAURIERS.

In presence of—

T. D. MERWIN,
H. S. JOHNSON.
